CENTERLESS GRINDING MACHINERY

Application filed August 24, 1925. Serial No. 52,056.

This invention relates to improvements in centerless grinding machinery and has particular reference to novel and improved mechanism for supplying workpieces to such machines and assuring proper discharge of the completed workpieces.

One of the objects of the present invention is the provision of improved mechanism for use in connection with a centerless grinder which will facilitate the successful supplying of individual workpieces in operative position within the machine.

A further object of the invention is the provision of a mechanism particularly adapted for the handling of small workpieces which will relieve the machine operator of the difficulties ordinarily attendant upon direct hand feed of the parts into the machine.

Another object of the invention is the provision of a structure which will make it possible to insure continuous operation of the machine and constant supplying of workpieces thereto while permitting of initial preparation of the pieces at a point distant from the machine.

An additional object of the invention is the provision of novel and improved mechanism for use in the in-feed method of centerless grinding which will successively position the individual workpieces in operative position in the grinding throat.

Other objects include the provision in in-feed grinding mechanism of a novel and improved method of positioning and handling workpieces during form grinding and a general simplification of the structural details, while preventing breakage of the parts in event of jamming of the workpieces. The foregoing objects and structure for accomplishment thereof should be readily understood by reference to the following specification taken in connection with the accompanying drawings, and it will be understood that we may make any modifications in the specific structural details shown and described within the scope of the appended claims without departing from or exceeding the spirit of the invention.

Figure 1 is a side elevation of a machine embodying the invention.

Figure 2 is a vertical sectional view with parts broken away.

Figure 3 is a horizontal sectional view as on the line 3—3 of Figure 2.

Figure 4 is a section on the line 4—4 of 55 said figure.

Figure 5 is a transverse section on the line 5—5 of Figure 2.

Figure 6 is a similar section on a different plane to bring out the action of the lower 60 cam member.

Figure 7 is a front elevation of the removable magazine.

Figure 8 is a perspective view of the magazine-retaining device and associate parts.

Figure 9 is a fragmentary vertical section 65 on the line 9—9 of Figure 4.

Figure 10 is a transverse section on the line 10—10 of Figure 7.

Figure 11 is a section on the line 11—11 70 of Figure 3 showing the wheels in work-receiving position.

Figure 12 is a similar section with the wheels in grinding position.

Figure 13 is a corresponding section showing the discharge position of the parts.

Figure 14 is a perspective view of the feed-controlling double cam member, and

Figure 15 is a fragmentary perspective view of the workrest.

The present invention deals primarily with what is known as in-feed centerless grinders, which is to say grinders in which the work is introduced within, acted upon and subsequently discharged from the grinding 85 throat by other than a continuous axial movement of the workpiece. In the present invention these results are intended to be automatically attained by suitably supplying individual workpieces from a magazine, axially 90 introducing the workpieces into the grinding throat when the wheels are in a separated position, subsequently bringing the wheels together to operate upon the work and then separating the wheels a sufficient amount to 95 allow the workpiece to drop down between the wheels and be discharged from the machine. The particular mechanism for causing this opening and closing movement of the wheels has been specifically illustrated and 100

claimed in co-pending application Serial No. 102,762, filed April 28, 1926, for example, and is not, therefore, particularly described.

In the embodiment of the machine chosen for illustration of the invention "A" designates the bed of the machine having supported thereon the grinding wheel "B" for rotary movement and being provided with a slide "C" for the housing "D" of the regulating wheel "E". The in and out movement of the regulating wheel "E" is controlled by adjusting member "F" preferably in the form of a screw. This member may be rotated by the handles "G" for position adjustment and may be given a back and forth operative movement either by the swivel nut and handle "H" or by the mechanism indicated at "I" as driven by the motor "K". Attention is invited to the co-pending application above referred to.

It will be noted that the grinding wheel "B" is shown as adapted for what is known as form grinding, that is to say, that it has a central plain portion as at 20 with beveled lateral portions as at 21. A wheel of this configuration operating upon a cylindrical workpiece will produce a piece having a central plain cylindrical portion 22 and cone point ends 23 as shown in Figure 3. To retain the work against the grinding wheel and to control the speed of rotation thereof, use is made of a regulating wheel "E" having a plain work-engaging surface 24 engaging the cylindrical portion 22 of the workpiece it being unnecessary for the regulating wheel to engage the shaped end portion 23. To facilitate axial introduction of the workpiece into the grinding throat the regulating wheel is beveled on the entrant side as at 25. In ordinary production the workpieces are produced of approximate size and form both centrally and terminally before they are brought into the grinding machine. As a result, when the grinding and regulating wheels are separated so that their portions proximate to an intermediate vertical plane, they are spaced slightly more than the diameter of the workpiece blank, the workpiece may be pushed between the two wheels, its pointed end 23 being guided into position by contact with the beveled portion 25 of the regulating wheel. The required separation of the wheels for this purpose is shown in Figure 11.

To support the work within the grinding throat between wheels "B" and "E" use is made of a workrest or support preferably carried by slide "C" and including a bracket portion 26 and a shaped work-receiving portion 27 having its surface inclined toward the regulating wheel and a top configuration substantially corresponding to the contour of the work to rest thereon. As the present machine is designed to operate upon workpieces of quite small diameter the rest or support is made from a heavy piece of material and is

centrally cut away or relieved as at 28 and 29 to receive the grinding and regulating wheels respectively, as should be readily understood by reference to the views on sheet 3 of the drawings. The width of the workrest is such that when the wheels are partly separated for introduction of the workpiece the rest will still support the work within the throat, while as the wheels are brought into operative engagement with the work, the workpiece will ride up on the inclined surface at 27. When the wheels are subsequently separated a greater distance the work will be discharged dropping down through the channel at 29 as shown in Figure 13.

Machines of the general character here described are designed for automatic production of workpieces accurate to within a fractional thousandth of an inch and at maximum rate. To attain this speed of production it is desirable that the work be automatically fed into the grinding throat. For this purpose the present invention includes a supporting block 30 carried by bracket 26 and having in its face a work-receiving groove 31 covered by face plate 32 forming a vertical passage of size to receive a single row of workpieces. In order that a continuous supply of workpieces may be supplied to said passage and thence to the grinding throat use is made of the removable work-receiving magazines. Such magazines comprise a back plate 33 having the work-groove or passage 34 and having hinged thereto the front or cover plate 35 fastened in closed position as by thumb nut 36. The cover plate has a plurality of sight apertures 37 for observance of the movement of the workpieces in the magazine.

It is intended that a plurality of interchangeable magazines be employed, each being provided with a positioning groove or recess 38 on its rear face for interlocking engagement with a tongue 39 on block 30 to accurately position the magazine for alignment of work-passage 34 with the passage 31 of block 30. To facilitate quick interchange of the magazines, block 30 has lug 40 in which is journaled the rock shaft 41 provided with a manually actuatable handle 42 and with the cam portions 43 which as the handle is rocked will force the removable magazine against tongue 39 and lock same in position as best illustrated in Figures 4 and 8.

It will be understood these magazines are filled with the workpieces to be operated upon and then brought into the machine. To prevent loss of workpieces from the discharge end of the magazine during handling, use is made of spring-keeper 44 having retainer 45 normally extending transversely of passage 34. This keeper is of greater length than the magazine so that when the latter is placed in position against block 30 and the locking cams tightened, the front face of the block below the magazine receiving shelf 46 will

engage the projecting end of the spring pressing it outward to withdraw stop 45 and allow downward movement of the workpieces as illustrated in Figure 4.

5 Coupled with the automatic regulating wheel reciprocating mechanism "I" as at 47 is rock-shaft 48 having rigidly secured thereon actuating cam 49 adjacent which is loosely mounted rock-arm 50. Arm 50 bears the 10 yieldably mounted plunger 51 engaging cam 49 whereby clock-wise rocking of shaft 48 will exert pressure against plunger 51 tending to swing arm 50 to the right but permitting movement of the shaft without movement of the arm in case an oversize workpiece or other obstruction prevents the customary and desired operation of the arm. Tension on the plunger may be varied by adjustment of cap-screw 52.

20 To rock arm 50 in the opposite direction a definite amount, an adjustable screw member 53 is carried by the arm and slidably received in passage 54 of cam 49, reverse or counterclock-wise movement of cam 49 causing inter-engagement of the cam and head of the screw 53 to withdraw the arm. A spring 55 may be employed to impart this counterclock-wise movement to the parts.

30 Pivoted to the upper end of arm 50 is pitman link 56 coupled to slide-block 57, by bolt 58. This slide-block bears an injector pin to move the lowermost workpiece from the magazine to a position within the grinding throat as is indicated in Figures 3 and 9 35 of the drawings.

In the feeding action the workpieces may either be allowed to move downward as an 40 entirety against the ejector pin so that the lowermost will be in position to drop in advance of the pin in its retracting movement in each instance, or use may be made of the special feed control mechanism here illustrated. This mechanism includes a pair of 45 stop plates alternately projecting into the path of discharge of the workpieces and cam means for automatically regulating the movement of these stop plates. Secured to bracket 26 is a guide block 60 within which is slidably 50 mounted the pair of plunger members 61 and 62 having the double beveled contacts 63 and 64 respectively adapted for engagement with the cam faces 65 and 66 of the upper cam and 67 of the lower cam. Springs 68 and 69 urge 55 the plungers inwardly tending to press their respective stop plates 70 and 71 transversely of the work-passage 31 thus preventing downward movement of the work-pieces therein. As slide 57 is shifted to the right or in work- 60 injection position, cam 67 will strike contact 64 moving plunger 62 rearwardly and withdrawing stop plate 71 from the path of movement of the workpieces. In this event, if 65 there is a workpiece resting on stop plate 71, the workpiece can drop down into alignment

with the feed plunger 59 as is shown in Figure 4. During this movement plunger 61 is stationary. On the withdrawing movement of the slide, contact 64 will ride down on cam 67 allowing stop plate 71 to move into closed 70 position. Subsequent to this movement cam 65 will engage plunger 63 rearwardly thereabove moving stop 70 so that a workpiece may drop down and rest upon stop plate 71.

On the return or feed movement stroke 75 cam 66 will again move plunger 64 backward but as one workpiece will be resting upon stop 71 the lowermost workpiece adjacent plate 70 can merely move into a position where it will be clamped between the end of the stop 80 and the side wall of the passage as shown in Figure 4, being then ready for quick downward movement onto the lower stop plate on the next return stroke. In this manner the delivery of small diameter workpieces is accurately controlled and liability of jamming or piling-up of the workpieces or introduction of more than one workpiece at a time into alignment with the injector is prevented.

85 From the foregoing description the construction and method of operation of the machine should be readily apparent and it will be seen that there has been provided an improved automatic mechanism by which small individual workpieces may be fed in a 90 continuous stream in proper sequence to the grinding throat and in which the grinding, ejection, and introduction of new workpieces is performed in proper sequence and satisfactorily formed articles of desired configuration 95 properly produced at a rapid rate by the in-feed grinding method.

100 Particular attention is invited to the automatic cyclic operation of the machine in which the regulating wheel is moved back from the grinding wheel and work rest a sufficient distance to allow a completed work piece to roll off the work rest and down through the discharge groove 29. Subsequently the wheels are brought together a sufficient amount to retain the work piece 105 between regulating wheel and work rest at which time a work piece is forcibly laterally introduced into the grinding throat by the 110 automatic work injector, after which the throat is decreased in width to properly grind the work piece and then opened up to permit of discharge thereof.

115 We claim:

120 1. A centerless grinder including a grinding wheel having a centrally recessed peripheral face with projecting side flanges and a regulating wheel having a plain portion opposing the centrally recessed face of the grinding wheel and having a beveled portion adjacent one of the flanges of the grinding wheel as an entrant guide for work introduced between the wheels and means for

axially shifting a work piece transversely of the face of the wheels.

2. A centerless grinder including a grinding wheel having a centrally recessed peripheral face with projecting side flanges and a regulating wheel having a plain portion opposing the centrally recessed face of the grinding wheel and having a beveled portion adjacent one of the flanges of the grinding wheel as an entrant guide for work introduced between the wheels, means for imparting a relative in and out movement to the wheels to open the grinding throat sufficiently to allow a workpiece to be axially introduced between the flange of the grinding wheel and the beveled portion of the regulating wheel and means for axially introducing a work piece transversely of the opposed faces of the wheels and guided by said beveled portion.

3. The combination with a centerless grinder including opposed grinding and regulating wheels, of a work-receiving magazine supported adjacent the wheels, a plunger carried by the grinder for shifting work from the magazine to the grinding throat between the wheels, means for actuating the plunger and a yieldable safety device in the actuating means.

4. The combination with a centerless grinder including opposed wheels providing a work-receiving throat, of an ejector plunger carried by the grinder for shifting work into the throat, a positive actuating device for the plunger, and a yieldable coupling between the plunger and actuating device permitting movement of the actuating device without shifting of the plunger when the path of the plunger is obstructed.

5. A feed mechanism for a centerless grinder including a work-feeding plunger, a chute for delivering work to the plunger, a plurality of work stops projectable into the path of movement of workpieces through the chute, means for automatically shifting the stops into and out of said path of movement, said means including independent cam members for the several stops, said cam members being movable with the plunger to cause the actuation of the stops to occur in timed relation with the movements of the plunger.

6. A centerless grinding machine including opposed grinding and regulating wheels, the grinding wheel having a recessed formed face and the regulating wheel having a plane portion opposing a portion of the formed face of the grinding wheel and a bevelled portion in the entrance side to provide a work guide, of means for automatically opening and closing the throat between the wheels and work supplying means disposed adjacent the grinding throat in offset relation to the axial position of the work within the throat, whereby a work piece projected therefrom will engage the bevelled entrant surface of the regulating wheel and be guided between the

wheels thereby and subsequently displaced to engage the contoured portion of the grinding wheel upon closing of the grinding throat and means for automatically transferring a work piece from said off-set work supplying means to the grinding throat in timed relation to the opening and closing of said throat.

7. A centerless grinder, including a bed, a grinding wheel supported thereon, an opposed regulating wheel mounted for in and out movement relative to the grinding wheel, a work guiding member mounted on the bed adjacent the grinding throat between the wheels and having a discharge portion axially aligned with the regulating wheel when in its retracted position, a plunger member for shifting work from the guide into the grinding throat, magazine retaining means carried by the work guiding member for securing a magazine in position to feed work thereto, a plunger for shifting individual work pieces from the work guide to a position within the grinding throat, and means coupling the plunger with the regulating wheel reciprocating mechanism to cause injection of a work piece in timed relation to the movement thereof and while said wheel is in a retracted position.

8. A centerless grinder, including a bed, a grinding wheel supported thereon, an opposed regulating wheel mounted for in and out movement relative to the grinding wheel, a work guiding member mounted on the bed adjacent the grinding throat between the wheels and having a discharge portion axially aligned with the regulating wheel when in its retracted position, a plunger member for shifting work from the guide into the grinding throat, magazine retaining means carried by the work guiding member for securing a magazine in position to feed work thereto, a plunger for shifting individual work pieces from the work guide to a position within the grinding throat, and means coupling the plunger with the regulating wheel reciprocating mechanism to cause injection of a work piece in timed relation to the movement thereof and while said wheel is in a retracted position, the plunger having cam portions controlling step by step movement of the work pieces in the guide toward the path of the work shifting portion of the plunger in timed relation to the operation thereof.

9. An automatic machine for centerless grinding, including a bed or support, opposed grinding and regulating wheels carried thereby, said grinding wheel having a recessed contoured surface, a work rest member disposed adjacent said surface, having a portion of reduced thickness providing a work support adjacent the grinding wheel and a discharge trough leading therefrom, means for automatically imparting an in and out movement to the regulating wheel as

respects the grinding wheel by way of said trough, whereby said regulating wheel will serve in combination with the rest to retain a work piece in position, to press the work piece against the grinding wheel or when withdrawn to permit discharge movement of the work piece through the trough, a work guiding member disposed adjacent the grinding throat and having a discharge portion aligning with the regulating wheel in its intermediate work retaining position, means for supplying work pieces to said guiding member, and means for shifting individual work pieces therefrom into the grinding throat in timed relation to the movement of the regulating wheel.

10. A centerless grinder including a bed, a grinding wheel carried by the bed for operation at a high or grinding rate of speed, an opposed regulating wheel carried by the bed and rotatable at a slow work controlling rate of speed, a work rest projecting into the throat between the grinding and regulating wheels, means for automatically separating the wheels a sufficient distance to permit a completed work piece to roll off the work rest in the direction of the regulating wheel, for subsequently closing the throat an amount sufficient to prevent such rolling off the work, and means for positively axially introducing a work piece in the throat when the parts are in said retaining position.

11. In grinding apparatus, in combination, a grinding wheel rotated at grinding speed, a regulating wheel opposed thereto and rotated at a relatively low speed and in a direction to present an operative surface traveling in a direction opposite from the direction of travel of the adjacent grinding wheel surface, a work support extending between said wheels, means for approaching and separating one wheel relative to the other, a magazine for holding a supply of work pieces and positioned to permit discharge of a work piece therefrom onto said work support but displaced axially from the position which the work piece is to occupy when operated upon by said two wheels, a plunger movable in a direction lengthwise of the axis of the work piece for moving a work piece discharged from said magazine into operative relation to said two wheels, mechanism for effecting discharge of work pieces one by one from said magazine, and means for actuating in predetermined sequence said wheel approaching and separating means, said plunger, and said mechanism.

GEORGE W. BINNS.
